ADJUSTABLE BELT

Sidney Hyman, New York, N. Y.

Application December 26, 1946, Serial No. 718,311

1 Claim. (Cl. 2—321)

1

This invention relates to belts, and provides improvements in extensible belts, and particularly, in such belts as are used in women's wear. The invention may have other utilities, but as now appraised, it is of maximum value when embodied in an extensible belt for feminine wear and of the decorative type.

An object of the invention is to provide a belt, the length of which may be adjusted to any one of a number of different belt sizes over a large range of sizes, more easily, quickly and conveniently than heretofore.

A further object is to provide a simple and inexpensive means of an improved type for permitting such adjustments.

Still a further object is to conceal all the parts functioning as above.

Another object is to provide a belt having all the advantages stated, and yet one which, whether expensively decorated so as to be sold as a de luxe and hence costly article of apparel, or more simply made so as to present an appearance of quiet and simple elegance but nevertheless saleable at very moderate prices, may be fabricated with ordinary leather working tools, and yet be very durable in use.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective front view of a belt pursuant to the present invention.

Fig. 2 is a top plan view thereof.

Fig. 3 is an enlarged vertical sectional view, taken on line 3—3 of Fig. 1.

Fig. 4 is a perspective view on a somewhat enlarged scale, showing a hook fitment.

Fig. 5 is an enlarged vertical sectional view taken on the line 5—5 of Fig. 2.

Fig. 6 is a view similar to Fig. 5, but taken on the line 6—6 of Fig. 2.

Fig. 7 is a view similar to Fig. 6, but taken on the line 7—7 of Fig. 1.

Fig. 8 is a fragmentary detail view in perspective, showing a modification.

Fig. 9 is a fragmentary detail view in elevation, showing another modification.

Fig. 10 is an enlarged horizontal sectional view taken on the line 10—10 of Fig. 9.

Fig. 11 is a view similar to Fig. 8, showing still a further modification.

2

Referring now in detail to the drawings, and first to Figs. 1—7, the extensible belt shown comprises two elongate flexible substantially flat members 11 and 12, of leather, plastic, cloth or any suitable material; these two members being adapted to be detachably connected together at two places, each to another portion of the other. As thus fastened together, the belt as a whole has an interior surface 14 and an exterior surface 15.

The members 11 and 12 at their rear ends, that is, at their ends remote from their portions where overlapped and joined at the front of the belt, have attached thereto loops 16 and 17, respectively. The loop on each member encompasses or encircles the other member.

Thus loop 16 of member 11 extends over the exterior surface of the belt, the arrangement being such that the member 12 is free to slide relative to this loop; and loop 17 extends over the interior surface of member 11, with here the arrangement such that said member 11 may be slid relative to the loop 17.

Attached to and in prolongation of the rear end of member 11 is a longitudinally stretchable hook-mounting strip 18, and this strip carries a hook fitment 19. The strip 18 is attached, as by one or more staples 20, to the rear end of member 11, with such attachment adjacent so as to be hooded over at the interior of the belt by the loop 16. The staple means 20 serves to seize and anchor the two ends of a unitary loop resulting from the self-aligningly folding over on itself of a strip of one-way elastic material, so that the bight of such loop is received in a transverse slot 19a of the hook fitment 19. Said strip of material is conveniently a well known one-way stretchable type of tape, sometimes also referred to as garter tape.

The loop 16 is separately stapled, as at 21, to the member 12.

The loop 17 is shown best in Fig. 6, as attached to its member by its decorative side-marginal stitching 17'; in which view said stitching 17', to simplify the drawing is illustrated along only one portion of its length. This loop, as indicated in Fig. 6, has its two mutually overlapping inner stretches connected together by staples 17''.

The loop 16 is shown in Fig. 1 as having matching decorative side-marginal stitchings 16'.

Suitably carried by the member 12 at the interior surface 14 of the belt is an inner ply or layer 12a of leather or the like stitched to a carrying or outer ply by decorative stitchings

such as shown at 22. Matchingly-decorative stitchings 22^a are shown as applied to section 11.

Said inner ply 12^a of member 12 is provided with a plurality of eyelets 23, 24, 25, 26 and 27 spaced at intervals longitudinally of the member 12. Desirably this spacing is such that each eyelet may appropriately be marked with a numeral representing a belt size. Thus, for instance, with hook fitment 19 engaged in eyelet 24 as shown, the belt will be a size "28," such as indicated by a marking (not shown) adjacent eyelet 24.

According to this arrangement, the hook fitment 19 and its associated parts, and also the eyelets 23-27, are all concealed when the belt is worn, being disposed completely interiorly thereof. As clearly seen from Fig. 2, the exposed rear surface of the belt is interrupted merely by the loops 16 and 17, which appear to be decorative only.

Where the front portions of the members 11 and 12 are to be overlapped and joined at the front of the belt, as the only step required to fix the belt in donned position, they are couplable instantly by a fastening means which, according to the invention as here illustrated, comprises a pair of snap fasteners, the post members 28 of which are outwardly upstanding from the exterior surface of member 11 and, the socket members 29 of which have their mouths facing inwardly of the belt from the interior surface of member 12.

In the case of the present invention, also, the apparently merely decorative loop 17 has a utilitarian function; this to mount a quickly efficacious means for finally instantaneously adjusting all parts of the belt, in regard to the belt size selected and effectuated by engaging the hook fitment 19 with the selected one of the eyelets 23-27, so that when the belt is placed on a waist of the appropriate size, the cooperant snap fastener members 28, 28 and 29, 29 are naturally thrown into alignment.

Thus, in finally donning the belt, when the front portions of the members 11 and 12 have been overlapped, relatively slight inward pressure applied against the exterior surface of the front end of member 12 brings both snap fasteners to fastened condition. The operative feature now being referred to is a finger tab 30 secured to the innermost of the two inner stretches of loop 17, as by a staple or staples 31, and so hidden from view while the belt is being worn.

The tab 30, which may be provided with an eyelet 31' to facilitate secure finger and thumb clasp, projects around the belt in the direction opposite to that of the projection of hook fitment 19. As soon as the hook fitment is engaged with a selected eyelet 23, 24, 25, 26 or 27, a simple quick manual pull on tab 30 draws both members 11 and 12 taut and so flat against each other thus to remove bellying of either member 11 or 12 relative to the other between loops 16 and 17.

The front of the belt may carry any decorative additions desired, for instance, a buckle (not shown), idle as such. In the present case, the front of the belt is shown as decoratively carrying a plurality of uniformly spaced solely decorative loops 32, with intervening metallic additions 33 suitably applied, as by bending over the free ends of their rearwardly projecting prongs 33^a present through the member 12.

Staples 34 may be used as shown in Fig. 7 to establish the loops 32 and anchor them to member 12.

In the modification illustrated in Fig. 8, a

V-converging pair of elastic tape elements 35, 35 are each stitched at one end and as at 36, 36, to the rear end of the member 11; these ends of said tape elements being spaced across the width of the belt. At their opposite ends, said tapes 35 converge for suitable securement to the desired form of hook member or its equivalent. The hook fitment 37 here shown is like the fitment 19, except that the slot 19^a is omitted, and, instead, two side extensions 38 are provided each with upstanding edge serrations 39, so that these latter may be folded over through 180° and clenched against the last mentioned ends of the tapes 35; with the consequence that, said serrations biting into the material of the tapes, the latter are given secure connection to the hook fitment.

In the further modification illustrated in Figs. 9 and 10, there is shown a hookingly functioning fitment 40 as an equivalent of the kind above referred. Fitment 40 is suitably attached to the belt in accordance with the invention, as, for instance, through the medium of an elastic tape 41 similar to the element 18; which fitment 25 carries a keyhole-shaped opening 42 for coaction with a selected one of a plurality of studs 43 spacedly carried by the belt in substitution for the eyelets 23-27.

Still another modification of engageable and 30 engaging elements for setting the belt to a desired size is shown in Fig. 11, where the hook engaging fitment is carried by one belt member and a line of spaced hook-like fitments are carried by the other belt member. Here the member 11 has stitched thereto an elastic-tape mount 44 for a ring 45, while on the inner ply 12^a of member 12 are fastened a plurality of hook fitments, of the kind long used in the shoe making art in connection with laced shoes, one of which 40 is seen at 46.

It is to be understood that the hook-mounting strip 18, 35 and 41 may be made of any suitable stretchable material such as; rubber, fabric, metal elastic spring, etc. and that this elastic 45 attachment allows for complete freedom of movement of the wearer and will provide complete comfort at all times. It also acts as an automatic tension release and eliminates pressure on the belt which prolongs the life of the belt.

This arrangement will permit the dealer to 50 avoid the need of maintaining a stock of different size belts.

While I have illustrated and described the preferred embodiments of my invention, it is to be understood that I do not limit myself to the precise construction herein disclosed and the right is reserved to all changes and modifications coming within the scope of the invention as defined 60 in the appended claim.

Having thus described my invention, what I claim as new, and desire to secure by United States Letters Patent, is:

An extensible belt comprising a pair of elongated members, a loop carried one by each of said members and each of said loops laterally encircling the other member, cooperative means carried by adjacent ends of said members whereby said end portions may be coupled to secure the belt on the waist of a wearer, means for preparatory modifying the length of the belt to conform with a selected waist size, the last named means including a plurality of engageable elements at spaced points along the interior surface of one of said flexible members and a co-

operative engaging element carried by the other of said members by an intermediate yieldable strap, and said engaging element adapted to engage any selected one of said engageable elements for the purpose described.
